[57] CLAIM

The ornamental design for a light and holster holder, as
shown and described.

DESCRIPTION

FIG. 1 is a perspective view of the light and holster
holder showing my new design;

FIG. 2 is a top plan view thereof;

FIG. 3 is a left end view thereof;

FIG. 4 is a right end view thereof;

FIG. 5 is a side elevational view thereof, the opposite
side being a mirror image thereof; and,

FIG. 6 is a bottom plan view thereof.

FIG. 1

FIG. 3

FIG. 4

FIG. 5

FIG. 6
